UNITED STATES PATENT OFFICE.

CLARENCE MARVIN, OF MATHER, WISCONSIN.

EXCAVATOR.

1,313,715.

Specification of Letters Patent.

Patented Aug. 19, 1919.

Application filed August 1, 1917. Serial No. 183,921.

To all whom it may concern:

Be it known that I, CLARENCE MARVIN, a citizen of the United States, residing at Mather, in the county of Juneau and State 5 of Wisconsin, have invented a new and useful Excavator, of which the following is a specification.

The present invention appertains to excavators and the object of the invention is 10 the provision of novel means for mounting and operating the dipper.

In the drawings, the invention is disclosed in a single vertical section, parts being broken away, and parts appearing in elevation.

15 The main frame 1 is of any desired construction, and is supported as shown at 2. Carried by the forward portion of the main frame 1 is a turn table 5, an inclined mast 6 having its lower end secured to the turn 20 table. The turn table 5 and the mast 6 are pivoted, as at 7, to the forward portion of the frame 1 to swing about a vertical axis. A U-shaped stirrup 8 is secured to the upper 25 end of the mast 6 and its terminals are connected by rods 9 with an anchor plate 10, nuts 11 being threaded upon the rods and bearing against the plate. The plate is pivoted, as at 12, to the upstanding forward portion 13 of the frame 1, the pivots 7 and 30 12 being in vertical alignment, whereby the rods 9 and the mast 6 may swing laterally. Guys 13' connect the frame portion 13 with the lower rear part of the frame 1.

As a means for turning the turntable 5 35 to swing the mast 6 laterally, the table has an arcuate flange 14 around which a cable 15 extends, said cable being secured intermediate its ends to the table, and the terminals of the cable 15 being wound in opposite directions upon a drum 16 carried by the frame 1, whereby when the drum is rotated in opposite directions, the mast 6 will be swung laterally in opposite directions.

The mast 6 is slotted as shown in 75, and 40 a boom 17 extends through the slot. An oscillatory guide 18 is trunnioned or pivoted, as at 19, within the mast 6 and the boom 17 extends through the guide, rollers 20 being carried by the guide, between which 45 rollers the boom extends. As the boom 17 is swung upwardly and downwardly, the guide 18 can oscillate with it, and the rollers 20 permit the boom to slide backwardly and forwardly.

50 As a means for advancing the boom 17, a

cable 21 is attached at one end, as at 22, to the mast 6 above the boom, and is looped over a pulley 23 carried by the rear end of the boom. From the pulley 23, the cable 21 is looped around a pulley 24 carried by the 60 mast 6 below the boom, and from the pulley 24, the cable 21 extends over the sheave of a pulley block 25 hung from the forward portion 13 of the frame 1. The other terminal of the cable 21 is wound upon a drum 26 65 carried by the frame 1, whereby when the drum is operated to wind the cable thereon, the looped portion of the cable 21 between the anchored end 22 and the pulley 24 will be drawn forwardly to move the pulley 23 70 and the boom 17 likewise. When the drum 26 is released, to enable the cable 21 to unwind therefrom, the boom 17 can be moved rearwardly as will hereinafter appear.

The rearward movement of the boom 17 75 is accomplished by a cable 27 having one end anchored to the boom, as at 29, near the forward end of the boom, and said cable 27 extends between guide pulleys 28 carried by the mast 6 near the lower end thereof. 80 The cable 27 extends from the pulleys 28 through the pulley block 25 and thence to a drum 30 carried by the frame 1 upon which drum said cable 27 is wound to pull the boom 17 rearwardly, the drum 30 being released when the drum 26 is operated to wind the cable 21 thereon. The drums 26 and 30 85 are thus operated alternately for moving the boom forwardly and rearwardly during the 90 operation of the excavator.

A dipper 31 has its bottom pivoted or hinged, as at 32, to the forward end of the boom 17, and when in receiving position, is 95 swung upwardly, being held in this position by means of a keeper 33 attached to the dipper and engaging a spring pressed latch stem 34 mounted on the boom 17. This construction will hold the dipper 31 in receiving position until released, and the forward portion of the dipper being heavier than the 100 rear portion thereof, will cause the dipper to tilt and dump, as seen in the drawing, when the dipper is released. A lever 35 is fulcrumed upon the boom 17 and is pivoted to the latch 34 to retract the latch and release the dipper. A release cable 36 is connected to the lever 35 and looped around a pulley 37 carried by the forward end of the boom 17. This cable 36 can be readily pulled 105 for swinging the lever 35 to retract the latch 110

34, whereby the dipper will tilt and dump. The dipper 31 has a lip 38 for scooping the dirt into it.

As a means for raising the boom and the dipper, a bail 39 is terminally pivoted to the sides of the dipper adjacent to the bottom thereof, and a cable 40 is used for raising said boom and dipper, one end of the cable being anchored, as at 41, to the upper free end of the mast 6. The cable 40 is looped through a pulley block 42 connected to the bail 39, and from the pulley block 42, the cable 40 passes over a pulley 43 carried by the mast 6 near the upper end thereof. From the pulley 42, the cable 40 extends over a pulley block 44 hung from the pivot member 12. From the pulley 44, the cable 40 extends to and is wound upon a drum 45 carried by the frame, whereby when the cable 40 is wound upon the drum, the dipper 31 and the boom 17 will be raised.

When the dipper 31 is in receiving position and latched, the mast 6 can be swung to the desired position by operating the drum 16. Then, by operating the drum 26 to pull the cable 21, the boom 17 will be forced forwardly and swing the forward end thereof and dipper 31 upwardly, to scoop the dirt or material into the dipper during its forward and upward movement. The cable 40 is wound upon the drum 45 to assist in raising the dipper. Then, when the dipper is raised, it can be moved to one side or the other by swinging the mast 6 in the desired direction, and the boom 17 can be retracted by winding the cable 27 on the drum 30. To dump the dipper, it is necessary merely to pull the cable 36, which will disengage the latch 34 from the dipper and permit the dipper to dump.

If desired, the excavator may be propelled by stepper 47 and an operating means 55-74 therefor.

Having thus described the invention, what is claimed as new is:—

An excavator comprising a frame; first, second and third drums journaled on the frame; an inclined mast supported on the frame; a guide pivotally mounted on the mast; a boom slideable in the guide; an idler on the rear end of the boom; an inner idler on the mast to the rear of the guide; an outer idler on the forward end of the mast; a bucket pivoted to the forward end of the boom; a sheave assembled with the bucket; means releasable from a remote point for holding the bucket against tilting on the boom; a first flexible element having its ends connected to the mast in advance of the guide and to the first drum, the intermediate portion of the flexible element being formed into oppositely projecting loops engaged, respectively, with the inner idler on the mast and with the idler on the boom; a second flexible element having its ends connected to the second drum and to the forward end of the boom; and a third flexible element having its ends connected to the third drum and to the forward end of the mast, the third flexible element passing over the outer idler on the mast and comprising a loop receiving the sheave which is assembled with the bucket.

In testimony that I claim the foregoing as my own, I have hereto affixed my signature in the presence of two witnesses.

CLARENCE MARVIN.
